UNITED STATES PATENT OFFICE.

WILLIAM H. LINCOLN, OF PHILADELPHIA, PENNSYLVANIA, ASSIGNOR TO LINCOLN FURNITURE COMPANY, OF PHILADELPHIA, PENNSYLVANIA, A CORPORATION OF PENNSYLVANIA.

SUPPORT FOR BEDS.

Application filed March 9, 1925. Serial No. 14,050.

My invention relates to the frame work for beds and is applicable to beds generally but, because of the frequent need of moving beds from room to room in hotels it finds 5 its greatest utility in connection with beds intended for use in hotels.

The main purpose of my invention is to support the bed frame wholly from the side rails and to make its support quickly and 10 easily removable by a structure involving a minimum of expense and complication.

A further purpose is to form a concealed supporting frame wholly separate and distinct from the bed frame and to rest the bed 15 frame removably upon it.

A further purpose is to secure rigidity and simplicity of application and construction along with unusual ease in assemblage.

A further purpose is to use an auxiliary 20 frame support taking the entire weight of the bed as a means of stiffening the side rails of the bed frame and the entire frame through the side rails.

A further purpose is to provide a bed 25 frame, comprising complete head and foot boards and side rails, with a wholly separate supporting structure from which it may be removed by lifting merely.

A further purpose is to support the bed 30 wholly free from the head and foot boards.

Further purposes will appear in the specification and in the claim.

I prefer to illustrate in the drawing one construction only, selecting one which is 35 simple, highly practical and reliable and which at the same time well illustrates the principles of my invention.

Figure 1 is a perspective view of a bed 40 carried by a supporting frame embodying my invention.

Figure 2 is a perspective, corresponding to Figure 1, but in which the bed frame is in skeleton only.

Figure 3 is a top plan view of the construction seen in Figure 1.

Figure 4 is a section of Figure 3 taken upon the line 4—4.

Figure 5 is a fragmentary vertical section, an enlargement of the section seen in 50 Figure 4.

Figure 6 is a horizontal section of Figure 5, taken upon line 6—6.

In the drawings similar numerals indicate like parts.

55 The bed frame or "bedstead" comprises

any usual head board 6, foot board 7 and side rails 8 and 9. Because the frame is to be separately supported, no casters are required for the head and foot board legs and the fastenings between the side rails and 60 the head and foot boards are more positive than the usual hooks. Any fastening will answer which is not released by the support of the head and foot boards by the side rails. I show a well known fastening in which the 65 side rail is recessed at 10 to permit longitudinal insertion of a bolt 11 fitting into the nut 12 within the head board or foot board.

The entire frame of the bed is supported by an auxiliary frame or carrier engaging 70 with the side rails. This carrier frame is shown in simple form as comprising castered legs 13, transverse supporting bars 14 and longitudinally extending connecting and bracing bars 15, all connected together in 75 any suitable way to secure the requisite strength and rigidity.

The supporting bars 14 are connected with the side rails by a joint which gives firm engagement in use but permits quick, so simple and easy release by merely lifting the side rails from them.

The supporting frame carries the spring, mattress and bedding as well as the bed frame. This makes it possible to lift the 85 bed frame as a unit from the supporting frame and mattress and to substitute another bed frame therefor, or to separately remove the bed parts therefrom.

I have found that the most satisfactory 90 type of joint between the supporting bars and the side rails is a dovetail joint and illustrate this in the drawings. The projecting dovetailed ends 16 extend into correspondingly dovetailed recesses 17 in the 95 side rails and, for convenience in cutting these recesses, extend entirely through the side rails so that the ends 18 of the dovetail projections 16 are flush with the sides 19 of the side rails. The appearance of the 100 side rails need not be marred by this as a finishing strip or border 20 can be placed over the ends of the dovetail projections.

The dovetail projections are preferably not as thick as the supporting bars and this 105 difference in thickness as well as the difference in which at the bases 21 of the dovetail projections is used to provide shoulders 22 which fit against the inner sides of the side rails, holding the edges 23 of the dovetail 110

projections tightly against the corresponding edges 24 of the recesses of the side rails and insuring a tight fit.

It is desirable to provide a slight vertical taper upon the edges 23 of the projections and the edges 24 of the taper so that the projections may be made to fit tightly in the recesses when fully home without interfering with easy and quick release when the bed is lifted from the supporting frame. I have obtained the best results when the parts fit together just tightly enough to require a slight jar for their release.

The points of engagement between the supporting frame and the side rails are preferably chosen at some distance from the ends of the side rails so that the frame will give a maximum stiffening to the side rails, permitting the use of lighter side rails where this is enough desired.

The use of my supporting frame greatly stiffens the bed against diagonal strain, making it unusually firm and rigid and thus protects the joints between the head and foot board respectively and the side rails.

It will thus be seen that I have provided a simple rigid construction easy to set up and take down, which greatly adds to the strength of the bedstead and not only pre-

vents substantial movement of any part of it but eliminates squeaking. The entire bed lifts off the frame without touching or unfastening any part of it and the appearance of the bed is in no way marred by the use of the frame.

It will be evident that other structures capable of securing all or a part of the benefit of my invention will occur to those skilled in the art in view of my explanation herein and it is therefore my purpose to include all such as come within the reasonable spirit and scope of my claim.

Having thus described my invention, what I claim as new and desire to secure by Letters Patent is:—

In a bed structure, a bed frame comprising head and foot boards and side rails rigidly united together, in which the side rails are adapted to support the weight of the head and foot boards, a spring-supporting frame inside the bed frame, having legs long enough to support the bed frame and having ends, the said ends being extended on both sides of the frame, and dovetailed joints between the extensions of the spring-supporting frame and the side rails wedging into rails to support the bed frame.

WILLIAM H. LINCOLN.
